(57) **CLAIM**

The ornamental design for a phone case, as shown and described.

DESCRIPTION

FIG. 1 is a front perspective view of a phone case showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded front perspective view thereof showing the components of the case separated for clarity of disclosure.

The broken lines shown in the drawings depict portions of the phone case in which the design is embodied that form no part of the claimed design.

For clarity of disclosure, the components of the phone case are shown separated in FIG. 9. Although the phone case in which the claimed design is embodied consists of separable components, the claim is directed to the overall ornamental appearance of the case in its entirety and does not extend to the ornamental appearance of each of the individual components in isolation.
